(57) **CLAIM**

The ornamental design for a battery for a mobile terminal, as shown and described.

DESCRIPTION

FIG. 1 is a top perspective view of a battery showing our new design;

FIG. 2 is a bottom perspective view thereof;

FIG. 3 is a top plan view thereof;

FIG. 4 is a bottom plan view thereof;

FIG. 5 is a front elevation view thereof;

FIG. 6 is a back elevation view thereof; and,

FIG. 7 is a side elevation view thereof.

The broken lines in FIGS. 1 and 3 are included for the purpose of illustrating features of the battery that form no part of the claimed design.
